AMES VAN WART, OF NEW YORK, N. Y.

Design No. 4,491, dated November 22, 1870.

DESIGN FOR A STATUETTE.

The Schedule referred to in these Letters Patent and making part of the same.

To all whom it may concern:

Be it known that I, AMES VAN WART, of the city of New York, in the county and State of New York, have invented a new and original Design for a Statuette; and I do hereby declare that the following is a full, clear, and exact description thereof, which will enable others skilled in the art to make and use the same, reference being had to the accompanying photograph forming part of this specification.

The photograph represents a side view of my design for a statuette.

This invention relates to a new design of a statuette, which represents a female figure, kneeling near, leaning against and embracing a standing cross. It is intended as a representation to the strophe—"Simply to thy cross I cling."

I claim as my invention—

The design for a statuette, as shown.

The above specification of my invention signed by me this 25th day of October, 1870.

AMES VAN WART.
